DESIGN FOR A SPOON OR OTHER ARTICLE OF FLATWARE

Charles F. Simms, Concord, N. H., assignor to
Concord Silversmiths Corporation, Concord,
N. H., a corporation of New Hampshire

Application December 19, 1936, Serial No. 66,646

Term of patent 14 years

To all whom it may concern:

Be it known that I, Charles F. Simms, a citizen of the United States, residing at Concord, in the county of Merrimack and State of New Hampshire, have invented a new, original, and ornamental Design for Spoon or Other Article of Flatware, of which the following is a specification, reference being had to the accompanying drawing, forming a part thereof.

Figure 1 is a plan of a spoon showing my new design.

Figure 2 is an edgewise view of the same.
Figures 3, 4 and 5 are sectional view taken on the lines 3—3, 4—4, and 5—5, respectively, of Figure 1.

I claim:—

The ornamental design for a spoon or other article of flatware substantially as shown.

CHARLES F. SIMMS.
